(57) **CLAIM**

The ornamental design for a garment, as shown.

DESCRIPTION

FIG. 1 is a front view of the garment in an open configuration showing my new design;

FIG. 2 is a rear view thereof;

FIG. 3 is a front view of the garment in a close configuration;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines shown illustrate portions of the garment that form no part of the claimed design.

1 Claim, 7 Drawing Sheets
